US0D1010626S

(12) **United States Design Patent** (10) Patent No.: **US D1,010,626 S**
(45) Date of Patent: ** Jan. 9, 2024

(54) **HEADPHONE**

(71) Applicant: **SHENZHEN SHOKZ CO., LTD.**,
Guangdong (CN)

(72) Inventors: **Haofeng Zhang**, Shenzhen (CN);
Zeying Zheng, Shenzhen (CN); **Sunjie Huang**, Shenzhen (CN); **Yonggen Wang**, Shenzhen (CN); **Jiang Xu**, Shenzhen (CN); **Xinnan Mao**, Shenzhen (CN)

(73) Assignee: **SHENZHEN SHOKZ CO., LTD.**,
Shenzhen (CN)

(**) Term: **15 Years**

(21) Appl. No.: **29/791,068**

(22) Filed: **Dec. 28, 2021**

(30) **Foreign Application Priority Data**

Jun. 29, 2021 (CN) 202130403569.3
Oct. 12, 2021 (CN) 202130669610.1

(51) LOC (14) Cl. **14-01**

(52) U.S. Cl.

USPC **D14/223**

(57) **CLAIM**

The ornamental design for a headphone, as shown and described.

DESCRIPTION

FIG. 1 is a perspective view of a headphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The shade lines in the Figures show contour and not surface ornamentation. The short dash broken lines indicate portions of the headphone that form no part of the claimed design.

1 Claim, 7 Drawing Sheets
